M. M. SCHEINBERG

GARTER AND METHOD OF MANUFACTURING SAME

Filed March 17, 1926

Fig. 1.

UNITED STATES PATENT OFFICE.

MORRIS M. SCHEINBERG, OF BROOKLYN, NEW YORK, ASSIGNOR TO HENRY SCHEINBERG AND MORRIS M. SCHEINBERG, COPARTNERS, DOING BUSINESS UNDER THE NAME AND STYLE OF STURM & SCHEINBERG, OF NEW YORK, N. Y.

GARTER AND METHOD OF MANUFACTURING SAME.

Application filed March 17, 1926. Serial No. 95,174.

This invention relates to improved garters and method of manufacturing same.

Pursuant to my invention, the garter of the men's type is provided with an ornamentation, particularly for the pad portion of the garter and of a form to facilitate the positioning of such ornamentation on the pad or other portion of the garter and also to eliminate folding, handling and other operations required pursuant to prior practices.

As embodied in a preferred form of my invention, the pad is provided with a layer of material, usually embroidered fabric, which is finished at its edges and of a contour corresponding to any regulation or other approved shape of pad or other portion of the garter and such ornamentation as may be desired. Such layer of material is positioned on the folded lining of the pad by suitable stitching, such stitching being otherwise required in the securing of the elastic fabric or other portion of the garter to the pad.

My invention is also applicable to the ornamentation of the pad portion of a man's garter, by the use of fabric as the material and ornamented by embroidery or the like to provide a finish for the outer edge of the fabric and with or without ornamentation within the contour of the material as may be desired.

Further features and objects of the invention will be more fully understood from the following detail description and the accompanying drawings, in which—

Fig. 1 is a perspective view showing a man's garter provided with an ornamented covering material for the pad portion, made pursuant to my invention;

Fig. 2 is a top plan view of a strip of fabric bearing a set or series of ornamentations formed by embroidery, from which the individual ornamented covering material is separated in the manufacture of the individual garters;

Fig. 3 is a perspective view of an individual ornamented material derived from the strip indicated in Fig. 2;

Fig. 4 is a sectional elevation on line 4—4 of Fig. 1;

Fig. 4^a is a sectional elevation on line 4^a—4^a of Fig. 1; and

Fig. 5 is a modification of Fig. 1, and also embodying my invention.

Referring to Fig. 1, the parts generally of the garter, excepting the pad portion, are of any regulation or any other approved form. The elastic pad is indicated at 10, one end 11 of which is sewed to the pad as described more fully hereinafter. The opposite end 12 of the elastic band 10 is looped through a regulation or other approved adjustable slide 13 and to adjustably carry the loop member 14, of regulation or other approved construction. The loop 15 of said loop member 14 cooperates with the stud 16 of the stud member 17. The stud member 17 as illustrated is provided with the slot 18 to afford suitable means for securing of the stud member 17 to the pad member, as by means of the overlapping stitchings 19.

The pad member comprises the rearward lining 20 of regulation or other approved form and material, and also an inner strip of stiffening material 20^a to give it body.

Pursuant to my invention, the forward layer 21 is formed of a suitable material to impart the desired finish and appearance, the edges of the layer material 21 being finished by stitchings 22, see Fig. 1, as by embroidery or the like. Preferably, the inner portion of the finish material 21 may be ornamented as is indicated at 23 or by any other desired or suitable form of ornamentation.

The pad member is provided with suitable means for connection with a sock, stocking or the like, which may be of the form as illustrated in the drawings, such as the clasp member 24, which cooperates with the stud 25 of the stud member 26, carried by the webbing 27 or equivalent.

In the form of the garter shown in Fig. 1, I may provide the extension 28, preferably of the material of the elastic band 10, whether elastic or not, or of other appropriate coloring or marking.

In the manufacture of men's garters and the like, the end 11 of the elastic band 10 is positioned between the finish material 21 and the rearward lining 20, to locate such end 11 within the line of stitching or stitchings 29, whereby the end 11 of the elastic band 10 is sewed to the rearward lining material 20. The line or lines of stitchings 29 are continued, say in the upper direction as viewed in Fig. 1, and then across the finish

material 21 as indicated at 30, thence downwardly as is indicated at 31, whereby the inner end of the extension 28 is jointly sewed to the rearward lining material 20 and the finish material 21, thence downwardly to the lowerly line of stitching 32 to jointly sew the finish material 21 and the inner end of the webbing 27 to the rearward lining material 20, and also the inner end of the webbing 33 of the clasp member 24.

If desired, a second and outer line of stitching 34 is applied to secure the inner end of the webbing 33 of the clasp member 24 jointly to the finish material 21 and the rearward lining material 20, which outer stitching 34 may be continued about the contour of the finish material 21, to provide for a superior style of finish for the more costly types of garters.

The finish material 21 is preferably of embroidered type and may be formed on an embroidering machine as a series of such embroidered finished portions 21^a, 21^b or the like, formed in the usual manner of embroidering a set of ornamentations upon a fabric base 35, usually in the form of an open mesh strip, to which the embroidered stitchings and ornamentations of desired design or designs are formed. The above results are obtained in one operation of the embroidering machine. The individual embroidered finished portions are separated from one another and from the base strip 35 by cutting or burning, or like procedure, well understood in the embroidery art. The individual ornamentations such as 21^a, 21^b, etc., are then applied to the individual garters as above described.

Pursuant to my invention, the heretofore necessary operations of folding the upper satin or other cloth of the pad to attain a finished edge and to prevent fraying, are eliminated.

Thus, my invention saves the time heretofore necessary in handling and folding the upper satin or other finishing cloth and the carrying of these parts to and from the folding machine.

Furthermore, my invention affords a most convenient and low-cost method of manufacture in the making of garters bearing an

embroidered or other ornamentation, in that the embroidering or other ornamental operations are performed on the outer finish material of the pad previous to assembling the same with the remaining parts of the pad member, as contrasted with the procedure of embroidering or otherwise applying ornamentation to the outer finish material after the assembly of the parts of the pad member.

In Fig. 5, the stud member 40 is secured in a suitable manner to the extension 28 of the pad member, in lieu of securing the stud member 17 to the finish material 21, as shown in Fig. 1. In the arrangement shown in Fig. 5, the ornamentation of the finish member 21 is exposed to the view of the observer wholly free from any other part of the garter.

Whereas, I have described my invention by reference to specific forms thereof, it will be understood that many changes and modifications may be made without departing from the spirit of the invention.

I claim:

1. The method of making a pad and appurtenant parts of garters or the like which comprises embroidering the outer material of the pad to have a contour conforming to the contour of the resulting pad and to have the contour portions of the outer material finished and simultaneously embroidering the front face thereof, assembling such finished outer material with the stiffening material of the pad and the appurtenant parts of the garter, and sewing the same to one another.

2. A pad and appurtenant parts of a garter or the like, comprising an outer material having its front face embroidered and a contour conforming to the contour of the pad and having its contour portions finished by embroidering, the stitches of such embroidering extending solely through the outer material, a layer of stiffening material, and stitchings securing said outer finished material and said stiffening material to the appurtenant parts of the garter.

In testimony whereof I have signed this specification this 15th day of March 1926.

MORRIS M. SCHEINBERG.
